SLIP SHEET APPARATUS

Original Filed March 9, 1937

UNITED STATES PATENT OFFICE

2,230,089

SLIP SHEET APPARATUS

Adolph Potdevin, Garden City, N. Y., assignor to
 Potdevin Machine Company, Brooklyn, N. Y.,
 a corporation of New York

Original application March 9, 1937, Serial No.
 129,787. Divided and this application March
 29, 1939, Serial No. 264,692

3 Claims. (Cl. 271—12)

This application, which is a division of my co-pending application Serial No. 129,787, filed March 9, 1937, Patent No. 2,158,552, May 16, 1939, is directed to an improvement in machines for handling material, such as paper, for example, which may be fed in a continuous length into the machine, cut off, printed and collected, my invention being particularly directed to a construction wherein a sheet of material, termed commercially a "slip-sheet," is inserted between adjacent lengths of superimposed printed material to prevent offset printing, that is to say, to prevent the ink on one piece of material being accidentally transferred to an adjacent superimposed length.

The machine is full automatic in operation and capable of operating at high rates of speed.

In the accompanying drawing:

Fig. 1 is a fragmentary elevational view of an embodiment of my invention; and

Fig. 2 is a view taken on the line 2—2 of Fig. 1.

Referring to the drawing in detail: 2 designates carrier chains adapted to receive bags 4 successively and to carry the bags through the printing mechanism (not shown) where the desired printing is applied to the face of the bags, the bags finally being delivered to a conveyor 6 traveling transversely of the carrier chains 2, this conveyor discharging the bags from the machine.

Spanning the carrier chains 2 at intervals and pivoted therein are gripper-carrying rods 8, each of which carries a plurality of grippers 10 adapted to grip the leading end of a length of material such as the bags 4, passing through the machine, the material, as illustrated in Fig. 1, being gripped between the grippers 10 and the flattened face of bars 12 carried by the chains and lying parallel with the rods 8. The grippers are spring closed.

The upper reaches of the chains 2 are moving from left to right, as viewed in Fig. 1, and it will be seen from this figure that each rod 8 is provided with a depending opening tail 14 which is adapted to engage a fixed stop 16 when a set of grippers has reached a position where the bag 4 overlies the transversely moving conveyor 6. In Fig. 1 I have shown a set of grippers in position where a bag is just being released upon the conveyor. After the opening tail has passed the stop 16 the grippers close again under the action of their closing springs, and will remain closed until the opening tail 14 engages opening cam 18 which opens the grippers and holds them open until the next bag reaches pick-up position, the tail 14 then riding off the cam permitting the

grippers to close upon the bag under the action of their closing springs. If desired this closing movement of the grippers may be retarded as disclosed in my copending application, above referred to.

As above pointed out, I provide for depositing a slip-sheet upon each bag or other material deposited upon the conveyor 6.

The slip-sheets are pre-cut and are fed into the machine from a stack. The stack of slip-sheets is designated 20.

The chains for carrying the slip-sheets to the conveyor 6 are designated 22. These chains are provided at proper intervals with rods 24 carrying grippers 26. The rods 24 are spring-actuated by springs 28 to close the grippers to grip a slip-sheet between the gripper jaws and a flattened bar 30 similar to the bars 12.

Each gripper rod is provided with an opening tail 32 adapted, as the chains advance, to engage an opening cam 34. This cam is so located that the grippers are opened at the proper instant to receive the leading end of the slip-sheet being forwarded thereto. Closure of the slip-sheet grippers is retarded by a cam 36 which is adapted to be engaged by a finger 38 with which each gripper rod 24 is provided. The grippers 26 are opened by a cam 40, located so that the slip-sheets are released as they come into position above the conveyor 6.

The stack 20 of slip-sheets is disposed at one side of and slightly above the grippers and chains and the slip-sheets are picked off the stack individually by suction nozzles or cups 42.

These nozzles or cups are carried in a suction head at the lower end of a vertically extending tube 44. This tube is provided with a lateral bracket 46, which pivotally mounts a short arm 48. The upper end of the arm or lever 48 is pivotally attached to the free end of a lever 50, 40 while the lower end of the arm or lever 48 is pivotally attached to the free end of a lever 52.

The lever 50 is pivoted on the machine frame at 54 and its free end is in line with the tube 44. A stop 56 at this end of the lever 50 limits the swing of the upper end of the tube 44 to the right, as viewed in Fig. 1. When the tube is against the stop, the tube is standing vertically, as shown in full lines in Fig. 1.

The lever 50 is provided with an offset 58, and a coil spring 60 has one end attached to this offset, the other end of the spring being attached to a lug 62 on the tube 44.

The lever 52 is pivoted to the machine frame by a rock shaft 64, this shaft also carrying a 55

lever 66 which is adapted to be actuated by a cam-controlled rod 68. The cam for actuating the rod 68 is designated 70, and is carried by a rotatable shaft 72. The shaft 72 also carries a cam 74 for actuating an arm 76 which is carried by a rock shaft 78, this shaft also carrying a lever 80. Pivoted to the upper end of this lever is a rod 82 extending toward the tube 44, the free end of the rod being bent about the tube.

10 The shaft 72 carries segmental rollers 84 co-operating with rollers 86 and with rollers 88. These rollers may be driven through any suitable gear train.

It will be apparent from all of the foregoing 15 that upon rotation of the shaft 72 to drive the cams 70 and 74 the actuating rod 68 will be raised vertically and the rod 82 moved to the right, to move the suction tube 44 vertically and swing the cup to the right to the dotted line position 20 shown in Fig. 1.

In operation, as the cup or suction head 42 is raised by lifting of the tube 44, a slip-sheet 90 will be removed from the stack 20 and carried to the right, as viewed in Fig. 1, so that the 25 leading end thereof will enter between the forwarding rollers 88 and the segmental forwarding rollers 84, and these rollers are so timed that at this instant the active surface of the segmental rollers will have rotated into position 30 to effect gripping of the slip-sheet 90, to advance the same along the inside face of the curved guide 92 which will guide the sheet into position to be picked up by a gripper 26. The machine is continuously running and the parts are so 35 timed that a gripper 26 will always be in position to engage a slip-sheet as the same is advanced to the chain 22. It will be understood that at the same time bags or other printed material are advanced by the chain 2, so that as a 40 printed bag 4 is dropped upon the conveyor 6 a slip-sheet 90 is dropped upon the bag.

Inasmuch as these machines are operated at 45 very high speeds, it is desirable, in order that the bags and slip-sheets may be properly deposited upon the conveyor 6, to provide a kicker arm 94 adapted to be oscillated into engagement with each slip-sheet as the same is brought into position above the conveyor 6. This kicker arm is

mounted on a rod 96 carrying the sprockets for the chains 22, the sprockets being freely rotatable on the rod. The kicker arm may be oscillated by a suitable cam such as disclosed in my copending application above referred to so as 5 to effect oscillation of the arm at proper intervals.

It is to be understood that changes may be effected in the apparatus hereinabove described without departing from the spirit and scope of 10 the invention.

What I claim is:

1. In a machine of the class described, the combination of a carrier for receiving slip-sheets, forwarding rollers for successively forwarding 15 slip-sheets to the carrier, a pivoted air nozzle, a rod for raising the nozzle, a cam controlling the rod and a rod for pivoting the nozzle toward the forwarding rollers, and a cam controlling said last-mentioned rod whereby the slip-sheets are 20 lifted successively from a stack and advanced to the forwarding rollers.

2. In a machine of the class described, the combination of a carrier for receiving slip-sheets, forwarding rollers for successively forwarding 25 slip-sheets to the carrier, a vertically extending air tube, an air nozzle carried at the lower end of the same, a rod pivotally connected to said air tube and adapted to raise and lower the tube, a cam-controlling said rod, a rod operatively 30 connected to said air tube and having a substantially horizontal movement to swing the air tube and nozzle toward the forwarding rollers, and a cam controlling the last-mentioned rod, whereby the slip-sheets are lifted successively from a 35 stack and advanced to the forwarding rollers.

3. In a machine of the class described, the combination of a carrier for receiving slip-sheets, forwarding rollers for successively forwarding slip-sheets to the said carrier, a pivoted air nozzle, means for raising said nozzle, a cam for controlling said nozzle-raising means, means for pivoting said nozzle, and a cam for controlling said nozzle-pivoting means whereby slip-sheets are 40 lifted individually from a stack of pre-formed 45 sheets and advanced to the forwarding rollers.

ADOLPH POTDEVIN.
